United States Patent Office

Des. 207,293
Patented Mar. 28, 1967

207,293

SEWAGE SEPTIC TANK

Carl W. Ferm, 950 Main St., South
Williamsport, Pa. 17701

Filed May 5, 1966, Ser. No. 2,184

Term of patent 14 years

(Cl. D91—1)

FIG. 1 is a side elevational view;
FIG. 2 is a top plan view of the tank;
FIG. 3 is a plan view of the open bottom half of the top half section of the tank; and
FIG. 4 is a plan view of the open top of the bottom half section of the tank.

I claim:

The ornamental design for a sewage septic tank, as shown and described.

References Cited by the Examiner

UNITED STATES PATENTS

D. 47,366 5/1915 Marcuse ----- D26—13
2,313,997 3/1943 Jackson.

OTHER REFERENCES

Product Engineering: Aug. 29, 1960, p. 113, storage tank.

WALLACE R. BURKE, Primary Examiner.

J. PAUL GUERTIN, Assistant Examiner.